DESIGN FOR A SHOWER PANEL FOR BATHTUBS

George Sakier, New York, N. Y., assignor to The
Accessories Company, Inc., New York, N. Y., a
corporation of New York

Application April 1, 1936, Serial No. 61,892

Term of patent 14 years

To all whom it may concern:

Be it known that I, George Sakier, a citizen
of the United States, residing at the city of New
York, in the county and State of New York, have
invented a new, original, and ornamental Design
for a Shower Panel for Bath Tubs, of which
the following is a specification, reference being
had to the accompanying drawing, forming a
part thereof.

In the drawing—

Figure 1 is a perspective view showing a shower
panel for bathtubs embodying my said design, and

Fig. 2 is a transverse section on the line 2—2
of Fig. 1.

I claim:

The ornamental design for a shower panel for
bathtubs, as shown.

GEORGE SAKIER.
